(57) **CLAIM**

The ornamental design for a sea harvest storage bag, as shown and described.

DESCRIPTION

FIG. 1 is an upper front left perspective view of a sea harvest storage bag of the present invention;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an upper front left perspective view of the sea harvest storage bag of the present invention in an alternative open configuration;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines in the figures show portions of the sea harvest storage bag which form no part of the claimed design.
